UNITED STATES PATENT OFFICE

PHILIP D'HUC DRESSLER, OF CLEVELAND, OHIO, ASSIGNOR, BY MESNE ASSIGNMENTS, TO SWINDELL-DRESSLER CORPORATION, OF PITTSBURGH, PENNSYLVANIA, A CORPORATION OF PENNSYLVANIA

KILN HEATING

Application filed March 16, 1928. Serial No. 262,221.

The general object of the present invention is the provision of a continuous tunnel kiln with improved kiln heating means. More specifically, the object of the present invention is to provide a continuous tunnel kiln with simple and effective means for burning coal, and especially slack coal or other cheap solid fuel, in combustion chambers distributed along the length of the firing zone of the kiln in such manner as to insure a desirable uniformity in combustion conditions and other desirable kiln operating conditions.

In the preferred practical mode of carrying out the invention I provide each combustion chamber with an automatic stoker of the under-feed type. It is one of the advantages of my invention that the stokers employed may well be wholly or in large part of standard construction and design, but my adaptation of stokers to the combustion chambers of a continuous tunnel kiln is characterized by various novel features of construction and arrangement contributing to convenient and effective utilization of such

stokers. Aside from the special advantages of particular features of construction and arrangement employed in the preferred embodiment of my invention, certain important general advantages are obtained by employing automatic stokers, and particularly automatic stokers of the underfeed type, in firing a continuous tunnel kiln. The use of such stokers makes it practically feasible to burn slack coal or analogous cheap solid fuel in kiln combustion chambers, under conditions, and particularly in firing certain wares, which have not permitted the use of such fuel heretofore made possible by the use of automatic

stokers. With the slow but normally continuous feed of the coal, its volatile constituents are driven out of the coal at a continuous and more or less uniform rate and largely cracked and burned in the combustion chamber, particularly if the stokers are of the underfeed type. In consequence, the rush into the kiln chamber of unburned rich gases of distillation, following each firing operation, which is experienced in the operation of open fired tunnel kilns with hand fir-

ing is avoided. A most important advantage of the invention is the great uniformity in combustion conditions which it is possible to maintain.

With hand firing it is necessary to maintain an approximate equality between the combustion chamber pressure and the pressure of the atmosphere to avoid the outrush of flame, or the inrush of cold air when the fire doors are opened, as they must be at frequent intervals with hand firing. With the present invention, however, it is possible to regulate the combustion chamber pressure solely with reference to the conditions desired within the combustion chambers and kiln. In particular, it is feasible and in many cases desirable to maintain a gas pressure in the combustion chamber which is appreciably above that of the atmosphere, so that the heating gases may be passed into the kiln chamber at high velocity facilitating their proper distribution in the kiln, without requiring an objectionable minus pressure in the latter.

It has long been recognized that a continuous tunnel kiln possesses a great inherent advantage over an intermittent kiln from the standpoint of fuel economy, but for many purposes, as in burning bricks and in analogous operations, it has not been possible heretofore to fully realize this advantage, because to insure kiln operating conditions necessary for production of a high grade product, it has been necessary to use a relatively expensive fuel, as oil or clean gas. With the present invention, however, it is possible to burn slack coal, which ordinarily is the cheapest possible fuel, efficiently, and with the maintenance of the kiln operating conditions required for the production of high grade wares, and heretofore obtainable only with more expensive fuels such as oil or clean producer gas.

The various features of novelty which characterize my invention are set forth with particularity in the claims annexed to and forming a part of this specification. For a better understanding of the invention, however, its advantages and specific objects attained with its use, reference should be had

to the accompanying drawings and descriptive matter in which I have illustrated and described preferred embodiments of the invention.

5 Of the drawings:

Fig. 1 is a plan view of a portion of a tunnel kiln;

Fig. 1A is a somewhat diagrammatic side elevation of a portion of the kiln;

10 Fig. 2 is an elevation in section on the line 2-2 of Fig. 1;

Fig. 3 is a section on the line 3-3 of Fig. 1 and Fig. 2;

15 Fig. 4 is a section on the line 4-4 of Fig. 3;

Fig. 4A is a partial section taken similarly to Fig. 4 illustrating a modified construction;

20 Fig. 5 is a section on the broken line 5-5 of Fig. 4; and

Fig. 6 is a section on the broken line 6-6 of Fig. 3.

In the drawings, A represents a continuous tunnel kiln through which bricks, or other wares to be fired, are continuously moved on kiln cars B running on track rails A'. As conventionally illustrated, each car is provided with perforated platform parts B' forming the top walls of channels B² between the piers 25 supporting the platform parts B', the channels B² leading from the outer side edges of the car toward the longitudinal center line of the latter. As shown, the kiln, which is of the open fired type, is heated by hot burning 30 gases and products of combustion passing 35 into the kiln chamber from the combustion chambers C distributed along the length of the firing or high temperature zone of the kiln and arranged at both sides of the latter. As shown, each combustion chamber C 40 communicates with the kiln chamber through a corresponding port A² which advantageously is downwardly inclined and located at such a level as to discharge gases into the adjacent 45 outer ends of the car channels B².

Each combustion chamber C is supplied with fuel by a corresponding underfired stoker mechanism D. As shown, the stoker mechanism comprises a metallic body portion extending into the corresponding combustion chamber C through a suitable wall opening C'. Each stoker mechanism is formed with a fuel trough or channel D², and a wind-box D³. The portion of the fuel trough 50 D² passing through the wall of the combustion chamber is circular in cross section, and a coal feeding device, shown as a conveyor screw D', is provided to advance coal from an external coal hopper D⁴ into the 55 combustion chamber through the channel D² at a suitable rate fixed by the rate of rotation of the screw D'. The fuel channel or retort D² is open at its upper side for approximately the full length of the combustion 60 chamber, and the coal advanced by the feed- 65

ing device D' wells up out of the retort D² and works out of the latter onto a grate at each side of the retort.

As shown in Figs. 4 and 5, each of these grates is formed by a row of plate-like grate bars E detachably secured to a rotatable shaft E' so as to form a dumping grate which may be tilted from time to time to dump accumulated ashes and clinker off the grate into the ash pit beneath.

Advantageously, however, instead of the simple dumping grate construction illustrated in Figs. 4 and 5, I may employ clinker breaking grates as shown in Fig. 4A, in which each shaft E' carries parts EA replacing the parts E of Figs. 4 and 5, and each provided with clinker breaking projections E⁵. The latter cooperate with side wall plates E⁶ and E⁷ to break up clinkers and to work the clinkers and ashes into the ash-pit when the shafts E' are rotated.

A characteristic feature of the preferred construction illustrated, is that the axis of each stoker, i. e., the direction of the fuel feed, is parallel to the axis of the kiln. This makes it possible to provide ash pit cleaning door openings F', and door openings F² through which the fire may be dressed and clinker removed from time to time if necessary, at one end of each combustion chamber, and to locate the coal hopper D⁴ and actuating mechanism of the corresponding stoker at the opposite end of the combustion chamber. Each opening F' and F² is normally closed by a corresponding door f' or f², respectively.

To permit the ready removal of each stoker D when this becomes necessary for repairs or other purposes, each stoker is slidably mounted on a wear plate A⁴ mounted on a pier A³ extending into each combustion chamber through the corresponding opening C', suitable provisions being made to seal the opening C' when the stoker is in place, these provisions including the removable metal parts D¹⁴ and D¹⁵ to which reference is hereinafter made.

To facilitate the insertion and removal of the stoker, the air supply connection to the wind box D³, if air is to be supplied under pressure as is ordinarily desirable, should be readily detachable from the stoker. As shown, the air supplied to the stoker wind box D³ for each combustion chamber, passes through a corresponding conduit G imbedded in the foundation of the combustion chamber and having an uprising discharge outlet G' which opens to the wind box through a port D⁵ in the bottom wall of the latter in the assembled condition of the apparatus. The inlet end G² of the pipe G extends up above the surface of the foundation at one end of the combustion chamber, and is connected to a blast supply pipe system Gg, receiving air from a blower G¹⁰. The air sup-

plied to the wind box D³ passes from the latter through ports D⁶ formed in or between removable tuyère sections D⁷ which form the upper sides of the coal channel or retort D², 5 and partly through suitable damper regulated openings D⁸ into the combustion chamber ash pit, passing upward from the latter between, or through ports in the grate bars E, and through the coal and ashes on the 10 grates.

In addition to the primary air for combustion supplied to each combustion chamber through the pipe G, secondary air for combustion is advantageously passed into the 15 combustion chamber through ports A⁵ in the outer side wall of the combustion chamber, from an air preheating and combustion chamber cooling system. That system, as shown, comprises an inlet pipe g imbedded in the 20 foundation portion of the corresponding kiln side wall, and supplying air at g' to a horizontal channel H extending under the corresponding port A² and having uprising portions H' at the sides of the chamber and a top portion H² above the port A² which communicates with the cooling space C⁵ in the 25 hollow roof of the combustion chamber.

The roof space C⁵ is connected by vertical channels or flues C⁶ to horizontal channels C⁷ and C⁸ in the end walls of the combustion chamber. The channels C⁷ and C⁸ communicate with a channel or space C⁹ in the outer side wall of the combustion chamber. The 30 space C⁹ is of arch form and supplies air to the ports A⁵ through an air chamber C¹⁰ from which the ports A⁵ open. The passage of air from the channel C⁹ into the chamber C¹⁰ may be regulated by a slide brick or damper C¹². An exhaust port C¹³ controlled 35 by a slide brick or damper C¹⁴ permits excess air employed in cooling the walls of the combustion chamber to escape into the atmosphere, when more air is needed for cooling 40 than is required for secondary combustion. It will be understood that the joints between the various damper and door openings and the corresponding dampers and doors, may be normally luted with fire clay or otherwise 45 made tight in accordance with the usual practice in the furnace art. Furthermore, the combustion chambers may be provided with the usual accessories and parts such as 50 pyrometer wells C¹⁵ and normally closed inspection openings C¹⁶ and C¹⁷.

The air supplied to the inlet end g² of each pipe g may be furnished by the blast piping system Gg which supplies air to the wind boxes D³ of the stokers D. In some cases both the primary and the secondary air may 55 be atmospheric air sucked into the kiln by the stacks or induced draft fans (not shown), employed in the usual manner to create the desired draft through the kiln. It is one of the advantages of the present invention, however, that a pressure above that of the atmos-

phere may be maintained in the different combustion chambers when this is desirable. The maintenance of such a combustion chamber pressure requires, of course, that the air supplied by the pipes G and g should be under a 70 pressure above that of the atmosphere. The maintenance of a pressure above that of the atmosphere makes it possible to secure a high gas velocity through the ports A², and correspondingly good distribution of the heating 75 gases among the channels B², without requiring a vacuum in the kiln chamber proper.

To regulate the distribution of air through the various pipes G and g, throttling dampers and flow regulating devices of known character may be employed. The primary regulation may advantageously be effected by means of orifice plates g⁵ and G⁵ having orifice openings of proper size, which are inserted in the individual connections from the pipe system Gg to the various pipes g and G.

Each stoker comprises a mechanism D¹⁰ including an oscillating ratchet lever D¹¹ for rotating the screw D'. This mechanism may be, and as shown, is of known adjustable type. The latter is given an oscillatory movement by a corresponding connecting rod I and eccentric I'. The eccentrics I' for the different stokers at each side of the kiln are mounted on a corresponding lay shaft I². As shown, the mechanism for rotating the two lay shafts I², one at each side of the kiln, comprise a driving motor J mounted on the roof of the kiln chamber and connected to the shafts I² through speed reducing and speed changing 95 gearing shown as including a speed changing device K of the well known Reeves drive type, a slow speed shaft L, and sprocket chains L' connecting the slow speed shaft L to the shafts I².

Advantageously, and as shown, the stokers D enter successive combustion chambers C at each side of the kiln, at opposite ends of the combustion chambers C, so that the coal hoppers D⁴ for an adjacent pair of combustion 110 chambers C are located in the space between those combustion chambers, and so that the ash pit doors for each intermediate combustion chamber face the ash pit doors of an adjacent combustion chamber. This arrangement separates the fuel supply systems for each combustion chamber from the ash removal system from that or any adjacent chamber, and obviously contributes to clean 115 and easy operating conditions. The arrangement economizes floor space moreover, since the stoker mechanism may be located wholly, or mainly within the margin of the space, the outer edges of which are defined by the edges of the combustion chambers remote from the 120 kiln axis. Furthermore, space is provided within said margin for workmen engaged in repairing the stokers, removing ashes and cleaning, adjusting, or renewing the grates and tuyère sections. The renewal of the 125

grates can be affected with comparative ease and rapidity whenever such renewal becomes necessary, as the doorways F² permit convenient access to the grate bar and may be made as conditions require.

10 Ashes may be removed from time to time through the ash pit door openings F' normally closed by the doors f'. The fuel beds may be raked and grate bars renewed or adjusted, when occasion requires through the doorways F² normally closed by the doors f². Each stoker may be quickly removed and replaced by another when major repairs are required. The stoker parts most liable to 15 injury are the tuyère sections D⁷. As shown, these sections are connected to the body portions of the wind box and retort walls by tongue and groove joints which permit the tuyère sections to be slid into and out of place 20 through the opening in the combustion chamber end wall normally closed by the parts D¹⁴ and D¹⁵. In consequence, a tuyère section which fails can be readily replaced without removing the stoker mechanism after removing the parts D¹⁴ and D¹⁵ for the purpose. The parts D¹⁴ and D¹⁵ are metal parts which are normally held in place by 25 separable resilient ties or connectors D¹⁶.

30 The described construction thus not only permits of the ready adjustment or renewal of grate bars and tuyère sections but also permits of other minor stoker adjustments and repairs.

35 It will be apparent to those skilled in the art that the present invention can be applied to various types of tunnel kiln without modification in the design or construction of the latter except that required for the addition of 40 suitable primary and secondary air supply connections to the combustion chambers when such connections are not already present in the type of kiln to which the invention is applied.

45 It will also be apparent to those skilled in the art that changes may be made in the form of the apparatus disclosed without departing from the spirit of the invention as set forth in the appended claims and that certain features of the invention may sometimes 50 be used to advantage without a corresponding use of other features.

Having now described my invention, what I claim as new and desire to secure by Letters 55 Patent, is:—

1. The combination in a continuous kiln having a kiln chamber with an inlet at one end and an outlet at its opposite end for the insertion and removal of material treated in 60 the kiln chamber and means for moving said material through the kiln chamber from said inlet to said outlet, of a plurality of combustion chambers at the sides of the kiln chamber for supplying heated gases to the latter at points distributed along the length 65

of the kiln chamber between said inlet and outlet, and automatic stokers for feeding solid fuel into the different combustion chambers.

2. The combination in a continuous tunnel kiln having a kiln chamber and a plurality of combustion chambers distributed along the sides of the kiln chamber and separately delivering hot gases thereto and automatic stokers one for each of said combustion chambers 75 and each adapted to feed solid fuel into the corresponding combustion chamber.

3. In a continuous open fire tunnel kiln having combustion chambers at the sides of the kiln chamber, the improvement which 80 consists in an underfeed stoker for each of said combustion chambers.

4. In a continuous tunnel kiln having a plurality of combustion chambers at one side of the kiln chamber, an individual stoker 85 mechanism for feeding solid fuel into and maintaining a fuel bed in each of the different combustion chambers and a common operating mechanism for the different stokers.

5. In a continuous tunnel kiln having a 90 plurality of combustion chambers at each side of the kiln, a separate stoker for feeding solid fuel into each combustion chamber, a stoker actuating shaft at each side of the kiln, and a separate operating connection between each of said shafts and the different stokers at the corresponding side of the kiln. 95

6. In a continuous tunnel kiln comprising a kiln chamber and a plurality of combustion chambers at each side of the kiln chamber and communicating with the latter, and a separate automatic stoker for feeding solid fuel into, and maintaining a fuel bed in each combustion chamber. 100

7. In a continuous tunnel kiln having a 105 plurality of combustion chambers at one side of the kiln, each of said combustion chambers having a stoker opening in one of its walls transverse to the length of the kiln and having an ash removal opening in the opposing wall transverse to the length of the kiln, and a stoker for each combustion chamber feeding solid fuel into the latter through the corresponding stoker opening. 110

8. In a continuous tunnel kiln having a 115 plurality of spaced apart combustion chambers alongside the kiln at one side of the latter and having a stoker opening and an ash removal opening formed the one in one, and the other in the second of the two opposing walls of each combustion chamber extending transversely to the length of the kiln, each intermediate combustion chamber having its said stoker opening facing the stoker opening in an adjacent combustion chamber, and having its ash removal opening facing the ash removal opening in an adjacent combustion chamber. 120

9. In a continuous tunnel kiln having a 125 combustion chamber at the side of the kiln 130

and a stoker adapted to feed coal into said combustion chamber in a direction parallel to the length of the kiln through a wall of said combustion chamber extending transversely to the length of the kiln.

10. In a continuous tunnel kiln having combustion chambers at the side of the kiln chamber, a stoker inlet opening in a wall of each combustion chamber extending transversely to the length of the kiln chamber, a stoker extending into the combustion chamber through the said opening and comprising a fuel channel, and means for feeding fuel through said channel, grates within the combustion chamber at the opposite sides of said fuel channel upon which the fuel advanced through said channel falls.

11. The combination in a continuous tunnel kiln of combustion chambers at the sides of the kiln chambers, automatic stokers for supplying solid fuel to the different combustion chambers, and means for supplying combustion supporting air to said combustion chambers to maintain a gas pressure therein exceeding that of the atmosphere.

12. In a continuous tunnel kiln having a plurality of combustion chambers at each side of the kiln, a separate stoker for feeding solid fuel into each combustion chamber and a common adjustable speed drive for the different stokers.

13. A continuous tunnel kiln having combustion chambers alongside the kiln chamber and each formed with a stoker opening in one of its walls transverse to the length of the kiln and having openings formed in its opposing wall at upper and lower levels for fire dressing and ash removal purposes, respectively.

14. In a continuous tunnel kiln having combustion chambers alongside the kiln proper and having an opening in one wall of each combustion chamber extending transversely to the length of the kiln, an underfeed stoker extending into the combustion chamber through said opening comprising separable tuyère sections, and removable means for closing a portion of said opening through which said tuyère sections may be replaced.

15. The combination in a continuous tunnel kiln of combustion chambers at the sides of the kiln chamber, and an automatic stoker removably mounted in each combustion chamber.

16. A continuous tunnel kiln having combustion chambers alongside the kiln with a stoker opening formed in the wall of each combustion chamber, means providing a supporting track in each combustion chamber for a corresponding stoker on which the latter may be slid into and out of place.

17. A continuous tunnel kiln having combustion chambers alongside the kiln with a stoker opening formed in the wall of each combustion chamber, a stoker provided with a

wind box for each chamber, means providing a supporting track in each combustion chamber for the corresponding stoker on which the latter may be slid into and out of place, and a blast conduit formed in the kiln sub-structure normally communicating with the wind box of the corresponding stoker.

18. In a continuous tunnel kiln having combustion chambers distributed along its sides and automatic stokers one for and feeding solid fuel into each of said combustion chambers, a stoker operating shaft at each side of the kiln chamber above the corresponding combustion chambers and operating connections for the different combustion chamber stokers extending downward from each shaft into the space between the corresponding side of the kiln chamber and the portions of the corresponding combustion chambers most remote therefrom and a driving mechanism for said shafts located above the kiln chamber.

19. In a continuous tunnel kiln having a plurality of combustion chambers at one side and automatic stokers one for feeding solid fuel into each of said combustion chambers, a stoker drive shaft located above the combustion chambers and operating connections between the different stoker mechanisms and said shaft.

20. The combination in a continuous tunnel kiln comprising a kiln chamber and combustion chambers at the sides of the kiln chamber, automatic stokers one for each combustion chamber and adapted to supply solid fuel to the latter and to maintain a fuel bed therein, regulatable means for supply primary and secondary air for combustion to each combustion chamber at the under and upper sides respectively of the fuel bed therein.

Signed at Cleveland, in the county of Cuyahoga and State of Ohio, this 14th day of March, A. D. 1928.
